[57] ABSTRACT

A device is disclosed for restraining the pages of a document. The device consists of a flat, horizontal base with a vertical member mounted at one side which projects upward and has disposed at its upper end an arm which extends out over the center of the base. Attached pivotally at about the end of the arm is a downward projecting rod-like member which swings in the plane of the arm but is restrained in its swing by elastic means mounted between the downward projecting member and the horizontal arm. In use this downward projecting arm engages the successive sheets of the document and holds them in a folded-back position.

DOCUMENT RESTRAINER

BACKGROUND OF THE INVENTION

Office workers often have the requirement to extract information from large numbers of data sheets such as computer print-out sheets, accounting records, parts lists and the like. Normally, the extraction of information from these types of records requires the individual performing the extraction to use one hand to write down the information he is extracting on a pad or piece of paper for future reference and the other hand as a reference pointer to maintain his place on the page of the document he is extracting from, thereby requiring the full utilization of both hands.

Bulky documents like those described above are usually bound, fastened or clipped together on a single edge, therefore the various pages must be folded back to permit the examiner of such records to review the data on the successive pages. Normally these pages, due to the resilience of the paper from which they are made, static electricity attraction of one page for the other, gravity and other like reasons tend to resist being folded back and away from the major volume of pages across their bound edge, thus requiring an individual extracting information from such documents to hold the folded-back pages in their folded-back position or to place a paper weight or some similar heavy object on top of the pages that have been turned back to prevent them from flipping forward and covering the page that it is desired to extract data from. Holding the pages back in a folded position with one's hand is unsatisfactory as a third hand would be required to pinpoint the information to be extracted. Use of paper weights and other similar heavy objects to hold back the folded pages is also unsatisfactory in that the folded-back pages normally present an uneven surface thereby causing the applied weight to slip off, thus permitting the folded-back pages to suddenly flip forward to cover the working area. The tendency of the pages of multi-page documents bound on a single edge to return to their original position from a folded-back position across their bound edge and thus cover the page of the document that is in use and the lack of a satisfactory retention method is a constant time-consuming aggravation that continually disrupts office processes, upsets workers and substantially increases the labor cost for such tasks.

The current invention provides an inexpensive device that firmly and positively retains the pages of bulky documents that have been folded back and away from the major volume of pages over their bound edges in their folded-back position thus preventing them from flipping forward to cover the page from which it is desired to extract information and thereby freeing both hands of the user of the current invention for the information extraction process.

The use of both hands solely for the information extraction process is particularly important to accountants, clerks and the like because the use of one hand to pinpoint the information to be extracted and the use of one hand to write with in a situation devoid of interruptions and sudden diversion of attention substantially reduce errors in the data extraction process, assist in the maintenance of tranquil worker attitudes and thereby increase efficiency, thus reducing labor cost.

SUMMARY OF THE INVENTION

This invention relates to a new and unique clerical device for use by office workers and the like doing tasks involving the extraction of data from multi-page bound or continuous documents.

An important object of this invention is to provide a means which will allow an individual who is extracting data from multi-page bound or continuous documents to have both hands free to perform the data extraction process; i.e., one hand available for pinpointing a specific line item which is to be extracted and one hand available for writing down the extracted data on a reference pad or similar memory-retention media.

Another object of this invention is to provide an inexpensive, mechanically simple, clerical device for the positive retention of the pages of multi-page bound or continuous documents in a folded-back position away from the major volume of pages in the document once they have been so placed.

Another object of the present invention is to provide a device which will provide positive retention of the pages of a multi-page bound or continuous document in a folded-back position without damaging, tearing or marring said documents.

Another object of the present invention is to provide a device which will provide positive retention of the pages of a multi-page bound or continuous document in a folded-back position yet allow their quick and easy release.

Yet another object of the present invention is to provide a device that will permit repetitive sheets of paper to be folded back and inserted so that they may be retained in a folded-back position without allowing previously inserted sheets to be released.

These and other objects are accomplished according to the invention which comprises a C-shaped stand with a cantilevered overhang containing an articulate rod-like projection at its forward terminus that extends from the cantilevered overhang vertically to the stand's base which is constructed of rigid material such as wood, plastic or metal or any type of organic, mineral or synthetic material that possesses rigidity and reasonable strength.

Other objects and many of the attendant advantages of this invention will be readily appreciated as the same become better understood by reference to the following detailed description when considered in connection with the accompanying drawings, wherein:

FIG. 1 is a perspective view of a preferred embodiment of the current invention.

FIG. 2 is a perspective view showing a preferred embodiment of the current invention as it appears in use.

FIG. 3 is an exploded perspective view of the paper retention mechanism of the current invention.

FIG. 4 is a side plane view of the paper retention mechanism of the current invention.

In the drawings, for the purpose of illustration, there is shown a preferred embodiment of the invention wherein similar reference characters designate corresponding parts throughout the several views.

Referring to FIG. 1, there is shown a preferred embodiment of the present invention which comprises a C-shaped stand 1 possessing an expanded hexangular base 2 from which a rear-mounted extension arm 3 rises perpendicularly to a point above the base whereupon it evolves into a cantilevered overhang 4 protrud-

ing forward at a 90° angle from the perpendicular extension arm 3 over the diametric center of said base 2 and parallel to the horizontal plane of said base 2 to a point directly above and even with the junction of an elongated, beveled protrusion 5 attached to and extending forward of the forward edge of said base 2 and the forward edge of the major portion of said base 3, said extension arm 3 containing a U-shaped slot 6 parallel to the horizontal plane of the stand's base and located in the forward half of the extension arm's 3 cantilevered overhang 4 for the purpose of mounting a spring-loaded pivotable block 7 from whose lower surface there protrudes a rod 8 of small diameter which extends downward and perpendicular toward the stand's base 2 to a point approximately three-quarters of an inch from its terminus whereupon it inclines rearward at an approximate thirty-degree angle from the vertical thence proceeding further downward and rearward to contact the hexangular base 2, said articulate rod 8 being continually urged to a near vertical position by spring or elastic means 9 of the pivotable block from which it protrudes and through which it is capable of rearward traverse and return from its static position if rearward pressure is applied and subsequently released.

Three non-skid pads of rubber, felt or other friction-generating material (34) are firmly attached to the lower surface of the hexangular base 2 to prevent slippage of the device about the surface on which it rests during use.

As shown in FIG. 2, there is a preferred embodiment of the present invention as it would appear in actual usage. The hexangular base 2 of the document retainer stand (1) is positioned slightly rearward of the bound edge 10 of the document 11 from which data is to be extracted.

The bottom edge 12 of the page of the document 13 which is to be inserted and restrained in a folded-back position is so maneuvered by the user of the present invention as to cause it to contact the forward edge of the elongated, beveled protrusion 5 which assists and directs the page to be inserted to sharply contact the forward lower inclined extremity 14 of the retention rod 8 with such force as to cause the retention rod 8 to swing slightly rearward across the hexangular base 2 in such manner that the arc of the swing causes the retention rod 8 to be lifted slightly from its point of contact with the hexangular base 2, or should previous document pages have been inserted, from the exposed surface of such documents. Immediately following the initiation of the swinging action of the retention rod 8, which is induced by the sharp contact of the edge of the document page 13 being so inserted and by a continued insertion pressure applied by the user, the inclined portion 14 of the retention rod 8 causes the document page 13 to slide down and under the displaced retention rod 8, thereby releasing all rearward pressures previously brought to bear against the retention rod 8; whereupon the continuous resilient urging of the retention rod 8 in a direction of clockwise rotation by the resilient means 9 attached to the pivotable block 7 causes the retention rod 8 to swing forward and over the inserted document page 13 so that it contacts and retains it in a folded-back position.

In FIG. 3 are shown the various components of the pivotable block assembly 7 which comprises an axis means 15; a rubber band 9 is employed as the resilient means to continually urge the pivotable block assembly

7 in a counter-clockwise direction, said rubber band being looped over the resilient means retention post 33 then extended downward and under the upper step 17 of the pivotable block assembly 7 and then upward 5 through the small-diameter hole 18 located in the middle step 19 of the pivotable block assembly 7 thence rearward across the top of the pivotable block assembly 7 to its terminus whereupon it proceeds downward and rearward to the resilient means retention post 16 upon 10 which it is secured, thus providing a continuous resilient urging to the pivotable block assembly 7 in a clockwise direction. The rotational stop-pin 20 has the purpose of blocking the clockwise rotation of the pivotable block assembly so that it is parallel and even with the 15 upper surface of the right arm 22 and left arm 23 of the U-shaped slot 6. The pivotable block assembly 7 whose lower surface resembles an inverted staircase in configuration comprises steps of three separate horizontal and parallel planes, each one above the other and possessing a small-diameter hole 18 perpendicular to the block's horizontal plane penetrating the diametric center of that portion of the pivotable block assembly 7 that comprises the middle step 19 and also possessing a second small-diameter hole 24 parallel to the pivotable block assembly's horizontal plane which penetrates the block from left to right at a point above and on line with the longitudinal junction 24 of the lower step 26 and the middle step 27 and at a point midway between the block's upper and lower surface. The 20 pivotable block assembly 7 further contains a resilient means retention post 16 which projects rearward from the diametric center of the rear of the uppermost step 17. Additionally, the pivotable block assembly 7 is fitted with a small-diameter rod 8 which protrudes perpendicularly from the diametric center of the lower surface of the block's lowermost step 36.

Additionally, FIG. 3 shows the detail of the U-shaped slot 6 contained in the forward half of the cantilevered overhang 4 of the extension arm 3. The U-shaped slot 40 6 is of such dimension that it will receive the block assembly 7 in such manner that the forward edge of the pivotable block assembly 7 is parallel and flush with the forward edges of the right arm 28 and the left arm 29 of the U-shaped slot 6 yet spacious enough longitudinally to allow for an opening 30 of approximately one-quarter of its length to exist between the rear end of the pivotable block 7 and the rearmost edge of the U-shaped slot 6 and of such dimensional width that the pivotable block assembly 7 will pivot freely between the right arm 28 and left arm 29 which configure the U-shaped slot 6. The cantilevered overhang 4 contains right and left axial bearing holes 31 and 32, respectively, in the forward terminus of each of the arms 28 and 29 forming its U-shaped slot 6 for the purpose of supporting axial means 15 about which the pivotable block assembly rotates.

Various changes may be made to the form of the invention herein shown and described without departing from the spirit of the inventor or scope of the claims.

It is claimed:

1. A device for restraining the pages of documents comprising in operative association an upright member disposed at the edge of a flat base and projecting upward therefrom, said upright member having a horizontal arm disposed at its upper end and extending away from said member across about the center of said base and parallel thereto; a downwardly projecting elong-

gated member havning an upper L-shaped portion pivot means pivotally attaching said downwardly projecting member near the terminus of said horizontal arm such that said L-shaped portion extends rearwardly toward the upright member and beyond the point of pivotal attachment and so that the downwardly projecting member swings in the plane of said arm and upright member and extends to the vicinity of the base; said downwardly projecting member being partially restrained in its swinging movement and returned to an approximately vertical position by elastic tension means attached at one end to the underside of said horizontal arm and passing over the top of the L-shaped portion of the downwardly projecting member rearwardly of said pivot means and attached at the other end to said downwardly projecting member.

2. The device of claim 1 wherein the end of the horizontally arm which projects over the base is forked to form two parallel side members with a space between

in which the L-shaped portion of said downwardly projecting member is pivotally mounted the axis of said pivot means projecting through said side members and L-shaped portion.

5 3. The device of claim 1 wherein said elastic tension means is a continuous elastic band.

4. The device of claim 1 wherein said elastic tension means is removably attached to projections on said horizontal arm and said downwardly projecting member.

10 5. The device of claim 1 wherein the lower portion of said elongated member is angled toward said vertical member.

15 6. The device of claim 1 wherein stop means are provided on said horizontal arm to prevent said downwardly projecting member from swinging beyond the vertical position in the direction away from said upright member.
